John L. Burroughs, Chicago, Ill.

Application March 30, 1953, Serial No. 24,274

Term of patent 14 years

(Cl. D56—4)

To all whom it may concern:

Be it known that I, John L. Burroughs, a citizen of the United States and resident of Chicago, in the county of Cook, and State of Illinois, have invented a new, original, and ornamental Design for a Radio, of which the following is a specification, reference being had to the accompanying drawing, forming a part thereof.

In the drawing, Figure 1 is a front perspective view of a radio showing my new design; and

Figure 2 is a rear elevational view thereof with

the base portion broken away for the convenience of illustration.

I claim:

The ornamental design for a radio, as shown and described.

JOHN L. BURROUGHS.
